UNITED STATES PATENT OFFICE.

FRANK A. WEEKS, OF PLAINFIELD, NEW JERSEY.

DESIGN FOR A FOUNTAIN-PEN-HOLDING RECEPTACLE.

No. 38,049.

Specification for Design.

Patented June 5, 1906.

Application filed March 10, 1906. Serial No. 305,415. Term of patent 7 years.

To all whom it may concern:

Be it known that I, FRANK A. WEEKS, a citizen of the United States, residing at Plainfield, in the county of Union and State of New Jersey, have invented a new, original, and ornamental Design for a Fountain-Pen-Holding Receptacle, of which the following is a specification, reference being had to the accompanying drawings, forming a part thereof, and in which—

Figure 1 is a perspective and Fig. 2 a top view of a fountain-pen-holding receptacle bearing and incorporating my design.

I claim—

The ornamental design for a fountain-pen-holding receptacle, as shown.

FRANK A. WEEKS.
